[57] CLAIM

The ornamental design for a portable radio telephone, substantially as shown and described.

DESCRIPTION

FIG. 1 is a left side, top and front perspective view of a portable radio telephone showing our new design;

FIG. 2 is a right side elevational view thereof;

FIG. 3 is a rear elevational view thereof;

FIG. 4 is a bottom plan view; and,

FIG. 5 is a left side, top and front perspective view of a second embodiment thereof, the sole difference being that portion of the front side panel below the bottom horizontal groove shown in FIGS. 1 and 2 of the first embodiment.

The broken line showing of an antenna shown in FIGS. 1, 2, 3 and 5 is for illustrative purposes only and forms no part of the claimed design.
